(74) Attorney, Agent, or Firm—Workman Nydegger

(57) **CLAIM**

The ornamental design for an eyeglass case, as shown and described.

DESCRIPTION

FIG. 1 is a perspective view of an eyeglass case showing my new design.

FIG. 2 is a left side elevational view of the eyeglass case shown in FIG. 1, the right side being a mirror image thereof; FIG. 3 is a front elevational view of the eyeglass case shown in FIG. 1, the rear being a mirror image thereof.

FIG. 4 is a top plan view of the eyeglass case shown in FIG. 1; and,

FIG. 5 is a bottom plan view of the eyeglass case shown in FIG. 1.

1 Claim, 2 Drawing Sheets
